C. S. HOWLAND

FILM HOLDER

Filed April 21, 1921

Fig. 1,

UNITED STATES PATENT OFFICE.

CHESTER SCOTT HOWLAND, OF NEW BEDFORD, MASSACHUSETTS.

FILM HOLDER.

Application filed April 21, 1921. Serial No. 463,338.

To all whom it may concern:

Be it known that I, CHESTER SCOTT HOWLAND, a citizen of the United States, and a resident of New Bedford, in the county of Bristol and State of Massachusetts, have invented a new and Improved Film Holder, of which the following is a full, clear, and exact description.

This invention relates to improvements in film holders, particularly to a film holding frame adapted to be used in the process of developing X-ray films, an object of the invention being to provide a holder which will firmly grip a film, which may be used to hold the film in the washing and developing baths and also to conveniently support the film while it is being dried.

A further object is to provide a device of the character stated, which will be simple and practical in construction, neat and attractive in appearance, strong, durable and efficient in use, and comparatively inexpensive to manufacture.

With these and other objects in view, the invention consists of certain novel features of construction and combinations and arrangements of parts as will be more fully hereinafter described and pointed out in the claims.

30 In the accompanying drawings:—

Figure 1 is a plan view of my improved film holder;

Figure 2 is a fragmentary view in longitudinal section therethrough on the line 35 2—2 of Figure 1;

Figure 3 is an enlarged fragmentary view in section on the line 3—3 of Figure 1; and

Figure 4 is a similar view on the line 4—4 of Figure 1.

40 Referring in detail to the drawings, my improved film holder comprises a U-shaped frame 1, provided around its inner edge with a forwardly projecting rib or flange 2. The upper extremities of the side arms of the frame 1 have secured thereto a transverse handle member 3, the ends of which extend beyond the sides of the frame. The ends of the handle member may be conveniently utilized for suspending the frame in a tank 45 or on a drying rack.

The intermediate portions of the legs of the frame 1 are connected by a cross piece 4. That edge of the cross piece which is adjacent the intermediate portion of the frame 1 is provided with a rib or flange 5, similar to the rib 2.

A rectangular frame 7 has one side hingedly connected to the cross piece 4 by a hinge 8. The frame 7 is provided around its inner edge with a rearwardly projecting rib 9, 60 adapted to cooperate with the ribs 2 and 5 to firmly grip a film, indicated by the reference numeral 10. It will be understood that the free edge of the frame 7 folds 65 against the intermediate portion of the frame 1. Guide brackets 11 carried by the legs of the frame 1 guide the folding movement of the frame 7. A securing device in the form of a channel member 12 is pivoted 70 adjacent one end on the frame 7, as indicated at 13, and is adapted to straddle the free edge of the frame 7 and the intermediate portion of the frame 1, as seen clearly in Figure 3.

75 Although I have illustrated one of the preferred embodiments of my invention, it will be apparent that various slight changes and alterations might be made in the general form and arrangement of the parts described without departing from the invention and hence I do not wish to limit myself to the precise details set forth, but shall consider myself at liberty to make such slight changes and alterations as fairly fall within the spirit and scope of the appended claims. 80

I claim:

1. A film holder including a U-shaped frame, a cross member connecting the ends of the U-shaped frame, a rectangular frame hinged to the cross member and adapted to 90 cooperate with one end of the U-shaped frame to hold a film.

2. A film holder including a U-shaped frame, a cross member connecting the ends of the U-shaped frame, a rectangular frame hinged to the cross member and adapted to cooperate with one end of the U-shaped frame to hold a film, means for removably locking the free edge of the rectangular frame and the intermediate portion of the U-shaped frame against relative separation. 95

3. A film holder including a U-shaped frame, a cross member connecting the ends of the U-shaped frame, a rectangular frame hinged to the cross member and adapted to cooperate with one end of the U-shaped frame to hold a film, means for removably locking the free edge of the rectangular frame and the intermediate portion of the U-shaped frame against relative separation, 100 said means comprising a channel member pivoted on the free edge of the rectangular 105

frame and adapted to straddle the free edge of the rectangular frame and the intermediate portion of the U-shaped frame.

4. A film holder comprising a U-shaped frame, a cross piece connecting the legs of the U-shaped frame, ribs on the U-shaped frame and cross piece, a rectangular frame hinged to the cross piece and ribs on the rectangular frame adapted to coact with the 10 first mentioned ribs to clamp a film therebetween.

5. A film holder comprising a U-shaped frame, a cross piece connecting the legs of the U-shaped frame, ribs on the U-shaped frame and cross piece, guide brackets carried by the legs of the U-shaped frame, a rectangular frame hinged to the cross piece and adapted to be guided by said guide brackets upon folding movement of the rectangular frame, and ribs on the rectangular frame adapted to coact with the first mentioned ribs to clamp a film therebetween. 15 20

6. A film holder comprising a U-shaped frame, a cross piece connecting the legs of the U-shaped frame, ribs on the U-shaped frame and cross piece, guide brackets carried by the legs of the U-shaped frame, a rectangular frame hinged to the cross piece and adapted to be guided by said guide brackets upon folding movement of the rectangular frame, ribs on the rectangular frame adapted to coact with the first mentioned ribs to clamp a film therebetween, and means carried by the rectangular frame for removably securing the free edge of the rectangular frame and the intermediate portion of the U-shaped frame against relative separation. 25 30 35

7. A device of the character described in claim 6, and including a transverse handle member connected to the extremities of the U-shaped frame and extending beyond the sides of the frame. 40

CHESTER SCOTT HOWLAND.
